Primary Examiner — Elizabeth J Oswecki(74) *Attorney, Agent, or Firm* — Ralph E. Jocke; Walker & Jocke(57) **CLAIM**

The ornamental design for a parcel transfer vault, as shown and described.

DESCRIPTION

FIG. 1 is a front, top, right side perspective view of a parcel transfer vault showing our new design;

FIG. 2 is a front, bottom, and right side perspective view thereof;

FIG. 3 is a left side view thereof;

FIG. 4 is a front view thereof;

FIG. 5 is a right side view thereof;

FIG. 6 is a back view thereof; and,

FIG. 7 is a top view thereof.

The broken dash lines shown form no part of the claimed design.

1 Claim, 7 Drawing Sheets(56)
